(57) **CLAIM**

The ornamental design for a vehicle antenna, as shown and described.

DESCRIPTION

FIG. 1 is a top perspective view of a vehicle antenna, showing our new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof;

FIG. 5 is a bottom plan view thereof;

FIG. 6 is a bottom perspective view thereof;
FIG. 7 is a cross-sectional view thereof, taken along line 7--7 of FIG. 4; and,

FIG. 8 is a cross-sectional view thereof, taken along line 8--8 of FIG. 3.

The broken lines showing a vehicle in FIG. 1 depict environmental matter and form no part of the claimed design. The broken lines in FIGS. 6 and 7 illustrate interior portions of the Vehicle Antenna that form no part of the claimed design.
